UNITED STATES PATENT OFFICE.

HENRY B. WILLIAMS, OF ROCHESTER, NEW YORK, ASSIGNOR OF ONE-HALF
TO LEMUEL A. JEFFREYS, OF SAME PLACE.

DRAFTSMAN'S CURVE.

SPECIFICATION forming part of Letters Patent No. 447,593, dated March 3, 1891.

Application filed July 11, 1889. Serial No. 317,246. (Model.)

To all whom it may concern:

Be it known that I, HENRY B. WILLIAMS, of Rochester, in the county of Monroe and State of New York, have invented a certain 5 new and useful Improvement in Draftsmen's Curves; and I do hereby declare that the following is a full, clear, and exact description of the same, reference being had to the drawings accompanying this specification.

10 My improvement relates to draftsmen's curves, and is designed to provide a ruling-edge which can be bent or adjusted to any desired form and fixed in that position, thereby avoiding the difficulties that occur in the 15 use of a stiff curve.

The invention consists in the construction and arrangement of parts hereinafter described and claimed.

In the drawings, Figure 1 is a plan view 20 of the instrument with the curve set in S form. Fig. 2 is a cross-section of the same in line x x of Fig. 1. Fig. 3 is an elevation of a portion of the device, looking in the direction of the arrow in Fig. 1.

25 The instrument is composed of a base A, a flexible strap B, and a set of arms C C C.

The base A consists of a stiff segmental bar, which may be cast or otherwise formed, and has preferably a raised rib a, which forms 30 the support for the arms.

The strap B is a strip of spring-steel or other suitable material which will readily bend, but will recover its straight form when freed from restraint.

35 The arms C C C are thin strips of metal provided with longitudinal slots b b. The front ends of the arms are pivoted to lugs c c, which are riveted to the flexible rule B, and the rear ends rest flat on top of the base A 40 and are secured thereto by set-screws d d, which pass through the slots b b of the stays. Washers f f are inserted between the set-screws and stays, and these washers are made of different thickness near the ends of the 45 instrument, as shown in Fig. 3, for a purpose presently to be described. The base A lies flat on the surface where the drawing is to

be made, while the rule B stands edgewise thereon, as shown in Fig. 2.

To adjust the curve the rule B is bent to 50 the desired form, and the set-screws d d are then turned down to clamp the stays C C on the base A. In this condition the rule is held stiff and can be transferred from one place to another and be used any desired number 55 of times. In bending the rule to make the adjustment the stays slide forward or back on the base and are retained in place by the screws. By the use of washers f f of different thicknesses the rear ends of the stays 60 C C are elevated, some higher than the others, so that they will lap over or past each other without interfering in making sharp bends.

By the use of this device the desired curve can be made throughout its whole length and 65 the whole outline of the line be drawn at once, which cannot be done with a stiff curve of general form; but the latter has to be changed in position to fit different parts of the line.

70 The instrument is of great value to all draftsmen, but especially those who have to lay out many curves, such as ship-builders, &c.

Having described my invention, I do not claim, simply and broadly, a bed-plate provided with slotted arms and set-screws for 75 conforming to a curved surface.

What I claim as new, and desire to secure by Letters Patent, is—

In a draftsman's curve, the combination of 80 a base, a flexible rule, stays pivoted at one end to the rule and resting at the other on the base, set-screws for securing the stays to the base, and washers between the stays and base, said washers varying in thickness under the 85 different stays, as and for the purpose specified.

In witness whereof I have hereunto signed my name in the presence of two subscribing witnesses.

HENRY B. WILLIAMS.
